UNITED STATES PATENT OFFICE.

URBAN WELDON, OF COHOES, NEW YORK.

APPARATUS FOR DYEING YARN.

SPECIFICATION forming part of Letters Patent No. 395,195, dated December 25, 1888.

Application filed December 16, 1887. Serial No. 258,070. (No model.)

To all whom it may concern:

Be it known that I, URBAN WELDON, a resident of the city of Cohoes, in the county of Albany and State of New York, have invented certain new and useful Improvements in Apparatus for Dyeing Yarn; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

15 Similar letters refer to similar parts in the several figures therein.

My invention relates to improvements in apparatus for dyeing yarn; and it consists of the novel construction and combination of 20 parts hereinafter described, and pointed out in the claims, the main features being a vat for containing the dye-stuff and a dipping-wheel rotary therein for supporting skeins of yarn and dipping the same in the dye-stuff at each 25 revolution of the wheel.

The objects of the invention are set forth in the following description.

Figures 1 and 2 of the drawings are respectively side elevation and cross-sectional 30 views of a pair of sticks employed in supporting skeins of yarn. Figs. 3 and 4 are similar views showing a modified form of sticks. Fig. 5 is an end elevation of a dipping-wheel and vat, with a portion of the head forming one 35 end of the wheel broken away to show the inner face of the opposite head. Fig. 6 is a central longitudinal section of the hub and one of the wheel-heads. Fig. 7 is a side elevation of two of the yarn-supporting sticks secured 40 together by end stays. Figs. 8 and 9 are longitudinal sections of one side of the dipping-wheel, showing modified forms of construction and arrangement of the yarn-supporting sticks.

45 In my apparatus a rotary dipping-wheel is provided with a series of flanged longitudinal sticks or rods, on which the skeins of yarn are separately supported, the said sticks being removably connected with the heads of the 50 dipping-wheel, which are provided with adjusting and securing devices. The sticks for holding yarn may be lathe-turned to form an-

nular flanges A', as shown in Figs. 1 and 2, or they may be plain sticks, A², inserted in perforated disks to form flanges A³. (See Fig. 3.) 55

I have represented three skeins of yarn, A⁴, as hanging from the sticks A A. It will be seen that the flanges A' serve to keep the skeins of yarn from impinging on each other to snarl and become entangled. 60

The dipping-wheel is composed of a hub, B, having at each end a circular head, B' and B², and gudgeons B³, projecting one from each end and rotary in boxes on the upper edge of the ends B⁴ of the vat B⁵. One of the gudgeons is provided with a pulley, B⁶, fixed thereon, to which power may be applied to revolve the wheel. The inner faces of the wheel-heads are provided with slots C near their periphery, adapted to receive the ends of one 70 of the pair of yarn-supporting sticks. The heads are also provided with a boss, D, near the hub, having slots D', adapted to receive the ends of the other one of the pair of yarn-supporting sticks. One of the pair of sticks 75 is inserted in one of the slots near the periphery of the wheel-heads and the other in one of the slots near the hub of the wheel-heads, as shown in the respective figures. The sticks are held in the inner or hub slots by the buttons a, pivoted at a' to the head. The buttons are held in place by a spring, a². The middle button in Fig. 5 is shown pushed to one side by the end of the stick. (Shown just outside of its slot in the position it occupies just as it 85 is being inserted in its slot.) After the stick enters the slot the spring a² forces the button to a position in a radial line with the stick, to hold it within its slot, as shown.

The position of the sticks in the peripheral slots may be adjusted radially of the wheel-head by means of the blocks a³, adapted to slide in and longitudinally of the slots. These blocks are provided with longitudinal slots a⁴, adapted to receive a bolt, a⁵, which passes 95 through the slot and through an aperture in the wheel-head, having on the opposite side of the head a thumb-nut, a⁶, by which the slotted block can be drawn tightly against the wheel-head, to hold it in any desired position in its retaining-slot. By loosening the thumb-nut the block can be slid longitudinally of its retaining-slot to the desired 100 position to give the required degree of tension.

to the skeins of yarn supported by the sticks A, and then secured in said position by screwing up the thumb-screws.

The position of the skeins of yarn is shown 5 by the dotted lines, and it will be observed that the skeins occupy planes radial to the dipping-wheel.

If the yarn-supporting sticks are so adjusted that the skeins are not taut between the 10 sticks, each end of the skein will fall below and away from the lower one of its pair of supporting-sticks once during each revolution of the dipping-wheel—*i. e.*, when the skein hangs vertically above and below the hub of 15 the wheel. Such falling away from the stick permits the dye-stuff to permeate all parts of the skein equally, which it might not do if the yarn were held taut against its supporting-sticks during the entire operation.

20 The sticks may be fixed at the proper distance apart by end stays, F, secured to the ends of the sticks, as shown in Fig. 7. When the sticks are so stayed, the inner faces of the wheel-heads may be provided with radial 25 slots extending from the periphery of the heads to points near the hub, as shown by

dotted lines E in Fig. 5. The sticks so stayed are shown in Fig. 9 secured in slots by buttons F'.

What I claim as new, and desire to secure 30 by Letters Patent, is—

1. In an apparatus for dyeing yarn, the combination, with the heads of a rotary dipping-wheel, of a series of longitudinal sticks which are provided with annular flanges for 35 separately holding skeins of yarn, substantially as and for the purpose described.

2. In an apparatus for dyeing yarn, a rotary dipping-wheel having heads which are provided with radial slots C at their peripheries, adjustable bearing-blocks placed in said slots, recessed hubs D, buttons a, and springs a², and a series of longitudinal sticks, A, provided with flanges A', the parts being constructed and combined substantially as shown, 40 for the purposes set forth.

In testimony whereof I have hereunto set my hand this 14th day of December, 1887.

URBAN WELDON.
